UNITED STATES PATENT OFFICE.

THOMAS A. DICKS, OF PITTSBURGH, PENNSYLVANIA, ASSIGNOR, BY MESNE ASSIGNMENTS, TO PITTSBURGH SCREW & BOLT COMPANY, OF PITTSBURGH, PENNSYLVANIA, A CORPORATION OF PENNSYLVANIA.

PROPELLER AND METHOD OF MAKING SAME.

Application filed January 9, 1928. Serial No. 245,596.

This invention relates to air craft propellers and more particularly to the construction and method of making hollow blades for such propellers.

Many and various forms of hollow metal propellers for use in connection with aircraft, have been proposed and patented, but an object of my invention is to produce a hollow metal propeller blade that is superior to any with which I am familiar.

Some of the prior hollow metal propellers are of complicated structure, others are of more or less simple structure, but employ folded or lapped edges; in others the plates constituting the hollow structure are so united that the juncture of the plates is located in the leading edge, or the leading edge is formed by the welding metal employed in uniting the plates. The objections to all such structures are obvious, and an object of my invention is to produce a light, rigid, durable propeller blade of simple structure, which is relatively simple and cheap to manufacture, and which overcomes objection to propellers heretofore proposed and known to me.

A further object of this invention is to provide a method of making a propeller blade, from two rolled blanks, and in which the leading edge of the blade is formed as an integral part of one of the rolled blanks, but in which lapped and folded edges are avoided.

Another object of this invention is to provide a method of making a propeller blade from two rolled metal blanks joined together by welding, and in which the weld is so formed and located that it not only does not detract from the strength and durability of the blade but adds to its effectiveness.

Still another object of this invention is the production of a hollow metal propeller blade which is formed from rolled metal plates, and which is of such strength and rigidity as to avoid the necessity of employing internal stiffening or strengthening braces or webs, except in connection with blades of unusual size.

A further object is to provide a new and improved means for and method of stiffening hollow metal propeller blades.

In the drawings, Figure 1 is a view in elevation of a blade embodying structural features forming a part of my invention and constructed in accordance with the method of

manufacture forming a part of my invention. Fig. 2 is an enlarged fragmentary view partially in section and partially in elevation of a modification of the blade of Fig. 1. Fig. 3 is a sectional view taken on line 3—3 of Fig. 2. Fig. 4 is a fragmentary view in elevation and is a continuation of Fig. 2. Figs. 5, 6, 7, 8 and 9 are sectional views of the blade of Fig. 1 and are so located relatively to each other that they respectively show the pitch angle of the blade at stations corresponding to section lines, 5, 6, 7, 8 and 9, of Fig. 1, and Fig. 10 is a view similar to Fig. 7 showing the modified blade of Figs. 2 and 4.

The blade herein illustrated as an embodiment of my invention, is constructed from two rolled metal blanks, welded together and which are so formed that the leading and trailing edges of the blade constitute a part of one of the blanks, but without the necessity of folding or lapping the blank to form these edges. As shown, the shank of the blade is formed as an integral part of one of the blanks, and the entire structure, when completed, forms an integral whole which is light, but which possesses such rigidity and durability as to avoid the necessity of employing internal strengthening webs or struts.

A propeller blade made in accordance with this invention consists of two parts, the blade proper designated by A, and its tubular shank, designated by a. As shown, the blade proper is made up of an outer camber member e, the outer surface of which is sometimes termed the suction face, an inner member f and an inlaid metal weld 3 which with the inner member f forms the inner camber member. The outer surface of the inner camber member is sometimes termed the pressure face of the blade.

In the form of blade illustrated in the drawings, the outer camber member e is hollow, that is, it is pressed or otherwise dished so as to form a hollow shell-like member as shown in Figs. 5 to 9 inclusive. At one end it merges into the tubular shank a, shown in Figs. 1, 2 and 3. In the blade illustrated, the shell-like camber member e and the tubular shank a are pressed from one and the same rolled metal blank. The inner member f, which is relatively flat, is pressed from another rolled metal blank and the inlaid metal weld 3, of appreciable width at its outer or

exposed surface, as shown in the drawings, forms, with the inner member *f*, the so-called pressure face of the blade.

In the pressing operation which shapes an outer camber member such as shown in the drawings, that portion of the blank, from which the tubular shank *a* is fashioned, is pressed into the form of a trough and, by one or more subsequent operations the shank is finished into tubular form with a joint extending longitudinally thereof, as shown at 1 in Figures 1, 2 and 3 of the drawings.

One of the features of my invention resides in the fact that the formation of the leading and trailing edges is accomplished without folding or overlapping the metal. As shown in the drawings, the leading edge is formed as a part of the outer camber member *e* but without the necessity of so distorting the blank, from which that member is formed, as to set up incipient cracks or objectionable strains within the metal. That portion of the trailing edge which is subjected to the greatest shock and to the greatest eroding action is also formed as an integral part of the member *e*, but here again, the construction is such that the formation of the trailing edge does not produce incipient cracks or set up objectionable strains in the metal.

30 The inner member *f* is stamped or otherwise formed from a blank of metal of substantially the same section as the outer camber member *e*. These members are tapered in thickness, being thinnest at the tip end of maximum thickness at the shank end. That portion of the blank from which the shank is formed is preferably of uniform thickness throughout its length.

As shown, the inner member *f* is slightly curved and so formed that it lies wholly within the marginal edge of the hollow outer camber member *e* with its outer surface substantially flush with the marginal edge of that member. That portion of the marginal edge of the outer camber member *e*, forming the leading edge of the blade, terminates in a lip, which as shown in Figs. 5 to 9 inclusive, shields the adjacent edge of the inner member *f*, and the inlaid metal weld 3 which unites the members *e* and *f*.

As shown in these figures of the drawings, the lip completes the leading edge of the blade and is, therefore, tapered transversely of the blade to provide the desired external curvature, so that it in effect terminates in a relatively sharp edge, which, as hereinafter noted, is backed up and reinforced by the inlaid metal employed in producing the weld.

In the embodiment illustrated, the blank forming the inner member *f* is scarfed or beveled around its entire outer edge and with the edge of the member *e* provides a more or less V-shaped trough or channel which extends entirely around the member *f*.

65 The welding operation is so performed that

the inner camber member of the blade is completed by the inlaid welding metal which, as shown in the drawings, forms a marginal surface of substantial width between the superficial edges of the members *e* and *f*. With this arrangement these two members are effectively and rigidly secured together and in addition, the inlaid welding metal contributes to the effectiveness of the blade, by forming an appreciable part of the pressure surface of the blade; by backing up and reinforcing the lip constituting a part of the leading edge of the blade and thereby stiffening that lip; and by, in effect, forming an integral stiffening flange along the portion of the member *e* which forms the trailing edge of the blade. Then, too, by employing the inlaid metal weld as illustrated, the desired blade contour can be readily obtained without unduly distorting or straining the metal. The location of the weld and, consequently, of the inlaid metal employed in making the same, is such that throughout the major portion of the length of the blade, the weld and the inlaid metal is, in the main, subjected to compression, as distinguished from other strains, with the effect that the resultant strain on the weld and the inlaid metal, is such as can be readily resisted during the normal operation of the blade. All these features contribute to the durability, rigidity and reliability of the blade.

A blade embodying my invention may be made of any desired and approved contour and the shank *a* may be formed from the blank employed in making the member *e*. It will also be apparent that the contour of the shank may be varied, to co-operate with any approved form of hub or blade mounting means, so long as it is of such form to contribute to the strength and rigidity of the blade proper.

As shown, the shank *a* is provided with shoulders *b* and grooves *c*, which may be formed in whole or in part during the pressing operation and which may be employed in connection with any suitable means for securing the blade in place on the hub.

As illustrated, the adjacent edges of the shank are secured together by an inlaid metal weld such as heretofore described, and which extends longitudinally of the shank along the joint 1, and is, therefore, not subjected to objectionable strains, during the normal operation of the blade. The adjacent edges of the shank are preferably scarfed or beveled, as shown, so as to provide a suitable groove for the reception of the inlaid metal employed in making the weld.

While the blade heretofore described is exceptionally strong and rigid, the occasion may arise, for example, in connection with large blades for further increasing the strength of the blade by means of an internal rib. Where an internal rib is desired or

deemed necessary I prefer to employ a web or rib such as illustrated in the drawings. As shown, a single centrally located and longitudinally extending web or rib *g* is employed. This rib preferably extends throughout the entire length of the blade proper and is welded to the inner face of the hollow camber member *e* prior to locating the member *f* in place thereon. In Figs. 1 and 5 to 9, inclusive, I have illustrated the rib *g* and the preferred method of securing it to the member *f*. The rib *g* is preferably tapered both in width and thickness from the shank end toward the tip end of the blade, and is so formed that its outer edge contacts with the member *e* substantially throughout the length of the member *e*. As shown, a series of spaced holes are bored or otherwise formed throughout the length of the member *f* and along the line of the rib *g*. As illustrated in Figs. 6 and 8, these holes are preferably countersunk or so formed that they decrease in cross sectional area from the surface of member *f* inwardly. The inner end of each hole should, however, be of a diameter substantially equal to the thickness of the web. The web is then secured to the member *f* by an inlaid metal welding at each hole 4 in the member *f*. After each weld is completed, the excess of weld metal is ground off or otherwise removed so that the surface of the welding metal 5 is flush with the surface of the inner member *f*.

The method of commercially manufacturing blades of this character may be carried forward as follows:—

The blanks, from which the members *e* and *f* are formed, may be rolled in such manner as to provide the proper taper or the taper may be subsequently provided. The blanks are then cut (preferably stamped) to a rudimentary shape and this cutting or stamping operation is preferably, though not necessarily, preliminary to the subsequent pressing operations in which the two members are given the desired and necessary contour. These preliminary operations include the scarfing or beveling of the edges of the members *e* and *f*. The member *f* is then placed in position, with relation to the member *e*, and the welding operation, heretofore described, is performed. As previously stated, the scarfing of the edges of one or both of the blade members provides a groove for the reception of the inlaid metal employed in the welding operation. This welding operation may be carried forward by the usual procedure in which the inlaid metal is deposited within the grooves formed for its reception and it is preferable to employ sufficient metal to overfill these grooves.

Where a blade is formed, as illustrated in the drawings, it is desirable to weld together the scarfed edges of the shank *a* prior

to fitting or locating the member *f* in place 65 with relation to the member *e*. Where a web or rib *g* is employed the operation of securing the rib in place on the member *e* is, of course, completed before locating the member *f* in place. In other respects the welding 70 operation is as above described. After the welding operation is completed the excess welding metal or overfill is removed, preferably by grinding, and the entire surface of the completed blade may then be polished or 75 otherwise treated for giving it the desired surface finish. It is also apparent, that any necessary machining operations may be performed after the welding operation.

The steps necessary for finishing the surface of the blade will depend somewhat upon the kind of metal employed and the finish desired. If a ferrous alloy relatively high in chromium and nickel (such as one having in the neighborhood of 18% chromium and 8% nickel) is used, the portion of the blade formed by the members *e* and *f* as well as the inlaid welding metal (if the same alloy is used for making the weld), may be given a high and lasting polish by ordinary grinding 80 and polishing operations.

By carrying out the steps above outlined, I am able to construct a relatively light yet rigid and strong hollow propeller blade which is capable of meeting all of the tests to 95 which such blades are subjected.

Having thus described my invention, what I claim is:—

1. A method of manufacturing an aircraft propeller blade which consists in shaping 100 from relatively thin metal a hollow member constituting the outer camber member and the leading edge of the blade, shaping from relatively thin metal a relatively flat blank constituting a portion of the inner camber 105 member of the blade of less area than the opening defined by the edge of the hollow member, depositing a margin of welding metal of substantial width around the edge of said blank to unite said blank and said hollow member and to reinforce the portions of said hollow member constituting the leading edge of the blade, and then finishing the surface of the metal so deposited, to complete the inner camber member of the blade. 110

2. A method of manufacturing an aircraft propeller blade, which consists in shaping from relatively thin metal a hollow member constituting the outer camber member and the leading edge of the blade, shaping from 120 relatively thin metal a blank constituting a substantial portion of the inner camber member of the blade, depositing a margin of welding metal of appreciable width around the edge of said blank to reinforce the portions of said hollow member constituting the leading edge and the trailing edge of the blade and to unite said hollow member and said 125

blank, and then in finishing the surface of the metal so deposited to complete the inner camber member of the blade.

3. A method of manufacturing an aircraft propeller blade, which consists in shaping from relatively thin metal a hollow member constituting the outer camber member and the leading edge of the blade, shaping from relatively thin metal a blank having a scarfed edge and constituting a substantial portion of the inner camber member of the blade, but of less area than the opening defined by the edge of said hollow member, fitting said blank in place within the opening of the hollow member, depositing a margin of welding metal of appreciable width between the scarfed edge of said blank and the adjacent edge of said hollow member to reinforce the edge of the hollow member and to unite said member and said blank, then finishing the surface of the metal so deposited to complete the inner camber member of the blade.

4. A method of manufacturing an aircraft propeller blade, which consists in pressing from relatively thin metal a hollow member constituting the outer camber member and the leading edge of the blade, shaping from relatively thin metal a blank constituting a substantial portion of the inner camber member of the blade, depositing welding metal around the edge of said blank to unite said blank and said member and to reinforce the portions of said hollow member constituting the leading and trailing edges of the blade, and finishing the surface of the metal so deposited to complete the inner camber member of the blade.

5. A method of manufacturing an aircraft propeller blade, which consists in pressing from relatively thin metal a hollow member constituting the outer camber member, the leading edge and the shank portion of the blade, pressing from relatively thin metal a blank constituting a substantial portion of the inner camber member but of less area than the opening defined by the edge of the hollow member, uniting the edges of the shank portion, depositing a margin of appreciable width of welding metal around the edge of said blank to unite said blank and said member and to reinforce the leading edge of the blade and the portion of said hollow member constituting the trailing edge of the blade, and finishing the surface of the metal so deposited to complete the inner camber member of the blade.

6. A method of manufacturing an aircraft propeller blade, which consists in pressing from sheet metal a hollow member constituting the outer camber member, the leading edge and the shank portion of the blade, pressing from sheet metal a blank constituting a substantial portion of the inner camber member of the blade, but of less dimensions than the opening defined by the edge of

said hollow member, securing a longitudinally extending rib to the inner face of said hollow member, fitting said blank into the opening of said hollow member and in contact with said rib, depositing a margin of welding metal of substantial width around the edge of said blank to reinforce the edges of said hollow member and to unite said member and said blank, finishing the surface of the metal so deposited to complete the inner camber member of the blade, securing said blank to said rib, and uniting the edges of said shank portion.

7. A hollow blade for aircraft propellers, comprising two rolled metal blanks, one shaped to form the outer camber member and the other shaped to form an inner member and lying wholly within the confines of said outer camber member throughout the effective length of the blade and secured thereto solely by means of an inlaid metal weld which lies wholly within the pressure face of the blade and behind the leading edge thereof throughout the effective length of the blade and which with said inner member constitutes substantially the entire pressure face of the blade.

8. A hollow blade for aircraft propellers, comprising two longitudinally tapered metal blanks, one shaped to form the outer camber member of the blade and the other shaped to form an inner member of the blade and lying wholly within the confines of said outer camber member throughout the effective length of the blade, and an inlaid metal weld uniting said inner and outer members, lying wholly within the pressure face of the blade and behind the leading edge thereof throughout the effective length of the blade and constituting an appreciable portion of the pressure face of the blade.

9. A hollow blade for aircraft propellers, comprising two rolled metal blanks having a shank forming portion as an integral part of at least one of said sections, one of said sections constituting the outer camber member of the blade and the other constituting an inner member lying wholly within the lateral edges of said outer camber member throughout the effective length of the blade and secured thereto solely by an inlaid metal weld which lies wholly within the pressure face of the blade and behind the leading edge thereof.

10. A hollow blade for aircraft propellers, comprising two rolled longitudinally tapered metal blanks, one shaped to form an outer camber member and a tubular shank, and the other shaped to form an inner member lying wholly within the bounding edges of said outer camber member throughout the effective length of the blade, and an inlaid metal weld uniting said members and lying wholly within the pressure face of the blade and behind the leading edge thereof.

11. A hollow blade for aircraft propellers, comprising two longitudinally tapered metal blanks, one shaped to form the contour and pitch angles of the outer camber member and the leading and trailing edges of the blade, and the other shaped to form an inner member lying wholly within the bounding edges of the outer member throughout the effective length of the blade, and an inlaid metal weld uniting said members, constituting an appreciable portion of the pressure face of the blade and lying wholly behind the leading edge thereof, said inner member and said inlaid metal weld constituting the pressure face of the blade.
12. A hollow blade for aircraft propellers, comprising a metal blank constituting the outer camber member and the leading edge of the blade, a second metal blank constituting a substantial portion of the inner camber member of the blade, an inlaid metal weld of substantial width surrounding said last mentioned blank, lying wholly within the pressure face of the blade and behind the leading edge thereof, and reinforcing the leading edge of the blade and uniting said blanks.
13. A hollow blade for aircraft propellers, comprising a relatively thin metal blank of decreasing thickness from the shank towards the tip end of the blade and constituting the outer camber member and the leading edge of the blade, a second relatively thin metal blank decreasing in thickness from the shank towards the tip end of the blade and constituting a substantial portion of the inner camber member of the blade, a marginal band of inlaid welding metal surrounding said second blank and uniting said blanks and lying wholly within the pressure face of the blade and behind the leading edge thereof and forming an appreciable portion of the pressure face of the blade.
14. A hollow blade for aircraft propellers, comprising a relatively thin metal blank of decreasing thickness from the shank towards the tip end of the blade and constituting the outer camber member and the leading edge of the blade, a second relatively thin metal blank decreasing in thickness from the shank towards the tip end of the blade and constituting a substantial portion of the inner camber member of the blade, a marginal band of inlaid welding metal surrounding said second blank and uniting said blanks and lying wholly within the pressure face of the blade and behind the leading edge thereof and forming an appreciable portion of the pressure face of the blade, and a centrally located longitudinally extending rib within the blade and secured to said blanks.

In testimony whereof, I have signed my name to this specification.

THOMAS A. DICKS.
